UNITED STATES PATENT OFFICE.

FRANK F. LANDIS, OF WAYNESBORO, PENNSYLVANIA.

SHOCK-DIFFUSER.

1,174,507.

Specification of Letters Patent.

Patented Mar. 7, 1916.

Application filed April 18, 1913. Serial No. 762,051.

To all whom it may concern:

Be it known that I, FRANK F. LANDIS, a citizen of the United States, residing at Waynesboro, Franklin county, and State of Pennsylvania, have invented and discovered certain new and useful Improvements in Shock-Diffusers, of which the following is a specification.

My said invention consists in certain improvements in the construction and arrangement of parts of shock diffusers for use on spring vehicles, particularly automobiles, of that general type shown in my application No. 702,228, filed June 7, 1912, whereby shocks incident to running over rough places, or obstructions, are diffused, or cushioned, and the objects recited in said application are accomplished in a more efficient and scientific manner, all as will be hereinafter more fully described and claimed.

Referring to the accompanying drawings which are made a part hereof, and on which similar reference characters indicate similar parts, Figure 1 is a detail side elevation of a vehicle spring of a common type as it appears attached to the frame of the body and axle of a vehicle, illustrating one of my shock diffusers in elevation as it appears in use with this particular type of spring, Fig. 2 a central vertical section through the shock diffuser structure illustrating the parts in the position they occupy during spring expansion, Fig. 3 a similar view illustrating the parts in the position they occupy during spring compression, and Fig. 4 a detail section on the dotted line 4-4 in Fig. 2.

In said drawings the portions marked A represent the casing, B a "floating" cylinder therein, C a piston in said cylinder, D a link or connecting rod, and E the operating lever.

The casing A is of appropriate form and entirely closed, being provided with a cap a and a screw-plug a¹ by which access may be had to the interior of said cylinder. Arms A¹ and A² are secured to one side of said casing by which it may be supported on one side of the vehicle spring, through the medium of a clip 11 and an appropriate bolt 12.

The cylinder B is open at the top and formed with an inwardly extending annular horizontal rim or flange at its lower end, leaving a large central opening. Said cylinder is mounted to slide vertically between guiding lugs 13 near the upper end of casing A and guiding lugs 14 near its lower end. Lugs 13 are formed with off-sets or shoulders

15 adapted to limit the upward movement of said cylinder. The lower end of said cylinder normally rests upon an annular raised seat 16 formed on the inner surface of the bottom of said casing A. Said annular seat is raised above the normal inner surface of said bottom and a restricted by-pass 17 is cut through said seat on one or more sides thereof. The distance between shoulders 15 of lugs 13 and seat 16 is sufficient to permit a limited "floating" movement of cylinder B between said points.

The piston C is fitted snugly within cylinder B and has an annular central opening 70 in its bottom around which is formed a valve seat.

The link or connecting rod D is connected to the piston C by a cross-pin 18 which extends through its sides and engages at its outer ends in elongated holes 19 in the sides of said piston, thus providing for a limited independent movement between said piston C and said connecting rod D. The lower end of said connecting rod D is globe-shaped and hollow, being adapted to fit snugly upon the seat surrounding the aperture in the bottom of the piston. The hollow portion extends for a considerable distance upward within said connecting rod, forming 80 an air chamber d. The upper end of said connecting rod is connected by a pivot 20 with a short arm 21 rigidly secured by a screw bolt 40 and interlocking faces on the inner ends of hubs 22 of the parts of arm E. 90 Said hubs are journaled in suitable bearings in the sides of casing A. Said operating arm E is composed of two parts connected at their outer ends by a bushing 41 and at their inner ends formed with hubs 22 which are journaled in suitable bearings in the sides of the casing A. Packing rings 42 are interposed to secure non-leaking joints around said limbs. The inner faces of said hubs are formed with corrugations or serrations adapted to engage and interlock with corresponding serrations in the opposite faces of the arm 21, which is interposed between them. A screw bolt 40 operates to secure the several parts rigidly together.

As will be readily seen, by loosening said screw the arm 21 and arm E can be adjusted in their angular relation to each other. By means of this adjustment the arm E can be adjusted to secure the proper movement of the piston in the operation of the apparatus. The outer end of said

arm E is connected by a clip 23 and bolt 24 with the side of the vehicle spring opposite that on which the casing is mounted.

The operation of my said invention is as follows: Referring to Fig. 3; the parts are shown in the position they occupy just as the vehicle spring is starting to compress under the impulse of a load, or sudden jar, or shock, incident to running over obstacles or rough places. The arm E has moved from the position indicated by dotted lines, which represents the full limit of the expansion movement, to that indicated by whole lines. This movement has elevated the connecting rod D until the pin 18 has contacted with the upper end of the elongated holes in the piston C, raising the lower end of said connecting rod from its seat around the opening in the bottom of said piston, and also raising cylinder B upward against the shoulders 15 of the lugs 13 and free from the seat 16 in the bottom of said casing. Two free passages are thus provided through which oil, or other suitable fluid, contained in cylinder A, may flow into the part of cylinder B beneath the piston C, one under the lower end of said cylinder and the other through the opening in the lower end of piston C, thus providing against any resistance to the compression of the spring except that provided by the spring itself and permitting it to compress as freely with this device attached as without it.

Referring now to Fig. 2; the parts are shown in position just after the spring has started to expand or recoil after compression, the arm E having moved from the extreme position of the compression movement, indicated by dotted lines, to the position shown by whole lines, which movement has served to carry the connecting rod D downward until the opening in the bottom of piston C is closed by the valve (consisting of the lower end of said connecting rod) being seated in the bottom of the piston. This also seats cylinder B upon the annular ridge, or seat, 16 in the bottom of casing A, forming an inclosed chamber within cylinder B beneath piston C filled with fluid and surmounted by the air chamber d. The further movement upward of the arm E under the expansion of the vehicle spring carries the piston C downward forcing the oil, or other fluid, in said chamber through the by-pass 17 into the space in casing A surrounding and above cylinder B, thus compelling the spring to expand slowly and easily and diffusing the shock incident to a sudden impact, or jolt, as when striking obstacles or running over rough surfaces.

It will be noted that the chamber d in the lower end of link or connecting rod D is an air chamber and that normally it is filled with free air. This provides an air cushion

to receive the first retarding check on the spring expansion. That is, the parts being in the position shown in Fig. 2 and the arm E continuing its upward movement, as indicated by the arrow, the air in chamber D will serve to cushion the first impact of piston C, in its downward movement, against the non-compressible fluid contained in the cylinder B beneath said piston, permitting said liquid to pass upward through the opening in said piston under pressure against the air in said chamber d until said air is compressed to a degree equal to the pressure under which the liquid is flowing outward through the by-pass 17. By this means the expansion is retarded under an elastic or yielding control, which relieves the vehicle and tires of undue strain and wear and effects a shock diffusion which is easy and almost imperceptible, relieving the riding over rough places and obstacles of much of the unpleasant experiences ordinarily incident thereto.

Having thus fully described my said invention, what I claim as new and desire to secure by Letters Patent is:

1. A shock diffuser for vehicles comprising a casing, a cylinder having a limited independent movement within said casing and a bottom formed to normally seat on the bottom of said casing to close the communication between the space surrounding said cylinder and that within it, a by-pass through said seat, a piston within said cylinder, a piston-rod connected with said piston to have a limited movement independent thereof, and an operating lever connected to operate said piston at one end and at the other end connected to one side of the vehicle spring, said casing being connected to the other side of said vehicle spring, substantially as set forth.

2. A shock diffuser for vehicle springs comprising a casing secured to one side of said spring and containing a cylinder mounted to have a limited independent movement, the lower end of said cylinder being adapted to seat on the bottom of said casing, a by-pass for establishing communication between the space in the cylinder under said piston and the space outside of said cylinder, a piston mounted in said cylinder, an aperture surrounded by a seat in the lower end of said piston, a piston-rod the lower end of which is adapted to fit upon said valve seat in the lower end of said piston and connected with said piston to have a limited independent movement, an operating lever connected at one end to operate said piston-rod, and the other end secured to the opposite side of the vehicle spring, substantially as set forth.

3. A shock diffuser for vehicle springs comprising a casing connected to one side of the spring, a floating cylinder in said cas-

- ing, a by-pass under the lower end of said floating cylinder, a piston in said floating cylinder, an opening through said piston, means for controlling said opening whereby 5 free communication is established into said cylinder beneath said piston on its upward movement and outward communication is shut off on its downward movement except through said by-pass, and an operating lever 10 connected to the other side of said vehicle spring and operatively connected to said piston, substantially as set forth.
4. A shock diffuser for vehicle springs comprising a casing connected to the parts 15 movable relative to the parts carried by said springs, a floating cylinder in said casing, a by-pass under the lower end of said floating cylinder, a piston in said floating cylinder, an opening through said piston, means 20 for controlling said opening whereby free communication is established into said cylinder beneath said piston on its upward movement and outward communication is shut off on its downward movement except 25 through said by-pass, and an operating lever connected to the said parts carried by said vehicle spring and operatively connected to said piston, substantially as set forth.
5. A shock diffuser comprising a casing 30 containing a liquid, a floating cylinder therein, a piston in said cylinder, means for operating said piston, means operable by the movement of said piston for establishing free communication into said cylinder at 35 both ends of the space under said piston, and means for cutting off and controlling the outflow from the said space, substantially as set forth.
6. A shock diffuser comprising a casing 40 containing a fluid, a cylinder submerged in the fluid in said casing and adapted to have a limited movement in relation thereto, a piston in said cylinder, means for reciprocating said piston, means operable by the 45 movement of said piston for opening free communication to the interior of said cylinder both through said piston and below said cylinder on one movement and for closing said communication on the reverse movement, said means being provided with a restricted 50 passage for controlling the outflow from beneath said piston, substantially as set forth.
7. A shock diffuser comprising a casing 55 containing a fluid, and provided with a free air space on top of said fluid, a cylinder submerged in the fluid in said casing and adapted to have a limited movement in relation thereto, a piston in said cylinder, means 60 for reciprocating said piston, a valve operable by the movement of said piston for opening free communication to the interior of said cylinder both through said piston and below said cylinder on one movement 65 and for closing said communication on the
- reverse movement, the seat for said cylinder being provided with a restricted passage for controlling the outflow from beneath said piston, substantially as set forth.
8. A shock diffuser comprising a fluid 70 containing casing connected with a part of a vehicle, a piston mounted in a cylinder within said casing and operatively connected with a part of the vehicle on the opposed side of its spring, means operable by the 75 movement of said piston for establishing free communication to within said cylinder both under the cylinder and through the piston on one stroke and for cutting off communication on the reverse stroke, said means 80 containing a restricted passage for controlling the outflow from beneath said piston, substantially as set forth.
9. A shock diffuser comprising a fluid 85 containing casing mounted on one side of the vehicle spring, a cylinder mounted in said casing to have a limited independent movement, a seat for the lower end of said cylinder formed to normally cut off communication between the space within and the 90 space without said cylinder, a restricted passage being formed therein, a piston mounted within said cylinder having an aperture in its bottom surrounded by a valve seat, a piston-rod the lower end of which is formed as a 95 valve and adapted to fit said valve seat connected to said piston to have a limited independent movement in relation thereto the lower end of said piston being formed hollow to provide an air cushioning chamber, 100 and an operating lever connected at one end to the opposite side of the vehicle spring and at its opposite end operatively connected to said piston-rod, substantially as set forth.
10. A shock diffuser comprising a fluid 105 containing casing mounted on one side of a vehicle spring, a cylinder within said casing mounted to have a limited movement in relation thereto, a piston within said cylinder formed with an aperture in its bottom 110 surrounded by a valve seat, a piston-rod connected with said piston to have a limited movement in relation thereto, and an operating lever connected with the other side of the vehicle spring at one end and at its 115 other operatively connected to said piston-rod, substantially as set forth.
11. A shock diffuser comprising a fluid 120 containing casing mounted on one side of a vehicle spring, a cylinder within said casing mounted to have a limited movement in relation thereto, a piston within said cylinder formed with an aperture in its bottom surrounded by a valve seat, a hollow piston-rod 125 connected with said piston to have a limited movement in relation thereto, and formed at its lower end to provide an air cushioning chamber above said valve seat, and an operating lever connected with the other side of the vehicle spring at one end and at its other 130

operatively connected to said piston-rod, substantially as set forth.

12. A shock diffuser comprising a casing, a piston in said casing having an opening, a valve mechanism for controlling said opening, an air chamber forming a part of said valve mechanism, and means for reciprocating said piston whereby during one movement free communication is permitted 10 through said piston and during the reverse movement said communication is closed and an air cushion provided against said movement, substantially as set forth.

13. A shock diffuser comprising a fluid 15 containing casing, a cylinder mounted therein having a limited floating movement adapted to open and close the bottom of said cylinder, a piston mounted in said cylinder having a limited floating movement in relation thereto which operates to open and close the top of said cylinder, and means for operating said parts, substantially as set forth.

14. A shock diffuser comprising a liquid 25 containing casing, a cylinder therein mounted to have a floating movement relative thereto adapted to open the bottom of said cylinder when moved in one direction and to close it when moved in the reverse direction, a piston in said cylinder having an opening therein, and means operable by the movement of said piston for controlling said opening, substantially as set forth.

15. A shock diffuser comprising a fluid 35 containing casing, a reciprocating cylinder therein, a reciprocating piston in said cylinder, an opening through said piston, means for controlling said opening containing an air chamber, and means for operating said 40 several parts, substantially as set forth.

16. A shock diffuser comprising a fluid containing casing, a reciprocating piston in said casing, means for providing for the free flow of the fluid from one side of said piston 45 to the other during the spring compressions, means for controlling the flow of the fluid from one side of said piston to the other during the spring expansion, and an air cushioning chamber arranged to coöperate 50 therewith, substantially as set forth.

17. A shock diffuser comprising a fluid 55 containing casing, a reciprocating piston in said casing, means for providing for the free flow of the fluid from one side of said piston to the other while the spring is taking compressions, tension means for controlling the flow of the fluid from one side of said piston to the other during the release of said tension, and an air cushioning chamber ar- 60 ranged to coöperate therewith, substantially as set forth.

18. A shock diffuser comprising a fluid

containing casing, a cylinder therein mounted to have a limited movement in relation thereto to open and close communication 65 through the bottom of said cylinder, a piston within said cylinder, an opening in said piston, a piston-rod embodying a valve for controlling said opening and connected to said piston to have a limited movement in relation thereto, and means for operating said piston-rod, substantially as set forth.

19. A shock diffuser comprising a fluid containing casing, a cylinder therein mounted to have a limited movement in relation 75 thereto to open and close communication through the bottom of said cylinder, a piston within said cylinder, an opening in said piston, a piston-rod embodying a valve for controlling said opening and also containing an 80 air cushioning chamber and connected to said piston to have a limited movement in relation thereto, and means for operating said piston-rod, substantially as set forth.

20. A shock diffuser comprising a casing 85 having a fluid containing chamber, a cylinder provided with valves one at its top and one at its bottom to freely receive the fluid at both ends during spring compression, means for closing said valves at both ends 90 of said cylinder during spring expansion, a restricted opening being provided between the face and the seat of one of said valves for permitting the gradual outflow of the fluid during spring expansion, and operating 95 connections, substantially as set forth.

21. A shock diffuser comprising a cylinder, a piston therein, valves at the top and bottom of said cylinder, means for simultaneously opening said valves during spring 100 compression, means for closing said valves to a restricted passage during spring expansion, and operating connections, substantially as set forth.

22. An apparatus of the character de- 105 scribed comprising a cylinder, a reciprocating piston therein, a restricted passage being provided from the chamber beneath said piston, a connection which actuates said piston, the lower end of said connection forming a spherical valve which closes a central opening in said piston while said piston is forcing a liquid through said restricted passage, and means for opening and closing said valve, substantially as set forth.

In witness whereof, I have hereunto set my hand and seal at Waynesboro this 24th day of March, A. D. nineteen hundred and thirteen.
